Primary Examiner — Karen E Kearney*Assistant Examiner* — Megan M Majcher Hartnett(74) *Attorney, Agent, or Firm* — Damian Wasserbauer; Wasserbauer Law LLC(57) **CLAIM**

The ornamental design for a display screen with graphical user interface, as shown and described.

DESCRIPTION

FIG. 1 is a front view of a display screen with graphical user interface in accordance with an embodiment of the present invention;

FIG. 2 is a perspective view of the design of FIG. 1;

FIG. 3 is a front view of FIG. 1 shown in the context of a different environment; and,

FIG. 4 is a perspective view of FIG. 1 shown in the context of a different environment.

The broken line showing of the tablet in FIGS. 1-2 and monitor in FIGS. 3-4 is for environmental purposes only and forms no part of the claimed design. The broken line showing of elements on the display screen illustrate portions of the article and form no part of the claimed design.

1 Claim, 4 Drawing Sheets(56)
